Specification for Design.

Patented Dec. 20, 1921.

Application filed February 17, 1921. Serial No. 445,896. Term of patent 3½ years.

To all whom it may concern:

Be it known that I, WALTER R. KAHNS, a citizen of the United States, residing at the borough of Brooklyn, county of Kings, city and State of New York, have invented a new, original, and ornamental Design for a Knob for Arm-Husks for Lighting-Fixtures, of which the following is a specification, reference being had to the accompany-

ing drawing, forming part thereof, in which—

Figure 1 is an elevation of a knob for an arm husk, showing my new design, and Fig. 2 is a top plan view of the same.

I claim:

The ornamental design for a knob for an arm husk for lighting fixtures, as shown.

WALTER R. KAHNS.
